MACHINE FOR PERFORATING NOTE-SHEETS.

1,280,578.

Specification of Letters Patent.

Patented Oct. 1, 1918.

Application filed August 11, 1914, Serial No. 856,266. Renewed February 28, 1918. Serial No. 219,729.

To all whom it may concern:

Be it known that I, CHARLES F. STODDARD, a citizen of the United States, and a resident of New York, county and State of New York, have invented an Improvement in Machines for Perforating Note-Sheets, of which the following description, in connection, with the accompanying drawings, is a specification, like characters on the drawings 10 representing like parts.

This invention relates to machines for making perforated note sheets for mechanical musical instruments; and pertains more particularly to mechanism for controlling 15 the respective feeding movements of the pattern or stencil, and the note sheet material to be punched, so as to maintain a proper relationship between the feeding operations.

Among other objects, the invention is intended to provide a simple feed controlling mechanism which shall operate practically infallibly to determine the proper relationship between the pattern feed and the feed 25 of the note sheet material.

The character of the invention may be readily understood by reference to the accompanying drawing, which shows diagrammatically one practical embodiment of 30 the invention which has been selected for illustration.

Referring to the drawings, the pattern or stencil sheet 2 is shown at the upper left hand corner of the sheet, and the note sheet material to be punched is shown at 3 at the 35 lower right hand corner of the sheet.

One of the functions of the apparatus shown is to cause the pattern sheet 2 and the note sheet material 3 to be fed in proper 40 relationship.

To illustrate one form of pattern sheet suitable to be used, the sheet 2 is shown as provided with perforations 4, corresponding to perforations intended to be punched in 45 the note sheet material 3. The note sheet material 3 may consist of a stack of superposed sheets which may be punched simultaneously.

The pattern sheet 2 is mounted upon a 50 spool 8, and is wound upon a take-up roll 9 driven by any suitable form of motor, as, for instance, a pneumatic motor M, shown diagrammatically. The motor M drives a crank shaft 10, having a pinion 11 which 55 meshes with the gear 12 upon the shaft of the take-up roll 9. As illustrated, the motor

M is a pneumatic motor supplied with suction from a duct 13; and this supply of suction is controlled as hereinafter described.

The pattern sheet 2 illustrates a prime controller of a punch selecting mechanism, which may be of any practicable type. For purposes of explanation, one practicable form of punch selecting mechanism is shown in the drawing as comprising a tracker bar 60 15 provided with vents to be opened by the perforations 4 of the pattern sheet 2. Each vent is connected by a duct 16 with the controlling valves of a power pneumatic 18. A chest for the several pneumatics 18 is 70 connected by duct 19 with a source of exhaust. As will be understood by those skilled in the art, when a vent of the tracker 15 is opened by a perforation 4, suction from the duct 19 is admitted to a power 75 pneumatic 18, causing the latter to collapse. When thus collapsed, the pneumatic 18 lifts a selector slide 20 in the perforating machine; and when the tracker vent is again closed permitting the power pneumatic 18 80 to expand again, the slide 20 is drawn downwardly to the position shown in the drawing by a spring 21.

It will be understood that there is a series 85 of the selector slides 20 corresponding each to a punch for punching a note perforation in the note sheet material. One complete set of selecting and punching devices is shown diagrammatically in the drawing; and it will be understood that these parts 90 are reduplicated as many times as may be necessary to provide for punching the desired number of rows of perforations.

The selecting mechanism comprises a horizontally reciprocating cross head 22 95 carrying selector pins 23, which are so mounted as to slide lengthwise readily in the cross head 22. This cross head 22 is connected by a link 25 with an eccentric upon the shaft 26, which is rotated continuously during the operation of the machine, thereby moving the cross head 22 and its gang of selector pins 23 toward and from the selector slides 20. A lever 28 fulcrumed at 29 bears at its upper end against the head 100 of the selector pin 23 and is held in engagement with the selector pin head by a spring 30, which tends always to rock the lever 28 in a contra-clockwise direction. The lower end of the lever 28 is pivotally connected to a selector bar 32, the right hand end of 105 which in the drawing rests in a slideway in

a vertically reciprocating cross head comprising the two connected parts 33, 34. The part 34 carries the punches 35, and the part 33 includes the punch-driving bar 36.

5 The cross head 33, 34 is reciprocated vertically in appropriate guideways by an eccentric upon the shaft 26, which is unnecessary to be shown. This suffices to show that for each complete revolution of the shaft 10 26 the cross head 33, 34 is moved downwardly and then upwardly through one complete reciprocation. The punches 35 are carried sufficiently loosely in the cross head 34 to permit them to drop against the note 15 sheet material 3 without punching the same except when a selector bar 32 has been moved far enough toward the right in the drawing to be interposed between the driving bar 36 and a punch head.

20 The punches 35 are arranged to slide vertically in a stripper bar 38, which overlies the note sheet material 3, supported at the punching point upon a die 39.

With the described arrangement, when 25 the cross head 22 is moved toward the left in the drawing, the lever 28 is permitted to rock slightly contra-clockwise, and thereby to move the selector bar 32 toward the right. If the selector slide 20 remains in the position shown, the movement of the selector pin 23 is arrested in such a position that the selector bar 32 is not permitted to move far enough to be interposed in driving position 30 between the punch 35 and the driver bar 36; but if the selector slide 20 has been lifted (by the opening of the corresponding 35 tracker vent), the cut out portion 40 of the selector slide is thereby positioned opposite the selector pin 23, permitting a sufficient movement of the pin, the lever 28 and selector bar 32 to move the latter into driving position and cause its corresponding punch to be driven through the note sheet material 3. As will be understood by those skilled 45 in the art, the horizontal reciprocation of the selector cross head 22 and the vertical reciprocation of the punch cross head 33, 34, are relatively so timed that the cross head 22 is moved toward the left to position the various selector bars 32 appropriately to the perforations to be punched, preparatory to the descent of the cross head 33, 34 to drive the selected punches through the note sheet material.

50 55 It is to be understood that the punch selecting and punching mechanism just described is merely illustrative, and any suitable equivalent or substitute may be employed.

60 65 The note sheet material 3 may be fed through the punching mechanism in any practicable manner, as, for example, by some such feeding mechanism as that described in United States patent to Davis No. 65 659053, dated October 2, 1900, one form of

which feeding mechanism is shown diagrammatically in the present drawings. As there shown, the note sheet feed mechanism is viewed in section on a vertical plane substantially bisecting the feed mechanism 70 transversely of the direction of feed, which is toward the right in the drawing. This feed mechanism comprises an upper apron 50 and a lower apron 52, each apron consisting of a pair of parallel sprocket chains 75 (only one of which is shown) connected by slats or cross bars 53 on the upper apron and 54 on the lower apron. The cross bars 53 and 54 on the respective aprons are so disposed that a cross bar 53 registers with 80 a cross bar 54 on opposite sides of the note sheet material 3 on the adjacent runs of the two aprons, so as to grip the note sheet material 3 between the cross bars with sufficient pressure to cause the note sheet 85 material to accompany the aprons during their movement. As this feed mechanism is shown, the aprons are driven intermittently by a pawl 56 engaging a ratchet 57 upon a shaft 58 of one of the sprocket 90 wheels 59 for the upper apron. Also fixed upon the shaft 58 is a gear 60 meshing with the gear 61 upon the shaft 62 for a sprocket wheel 63 of the lower apron. The pawl 56 drives this ratchet 57 in a contra-clockwise 95 direction and thereby, through the gears 60 and 61, drives the two aprons in the directions indicated by the arrows in the drawings.

The pawl 56 is reciprocated by a pitman 100 65 connected to an eccentric 66 upon the shaft 26. The eccentric 66 is so disposed upon the shaft 26 that the aprons 14 and 15 remain at rest during the downward movement of the cross head 33, 34 to drive the 105 punches; and when the cross head 33, 34 is moved upwardly, the eccentric 66 causes the aprons to be driven through one feed step so as to present a new part of the note sheet 110 material 3 in position to be punched.

The description thus far has pertained to the mechanism for selecting the punches and operating them to punch the note sheet material, and the feed mechanism for moving the note sheet material through the punching mechanism. The manner in which the prime selecting device illustrated by the pattern sheet 2 is caused to be fed in proper relationship to the feed of the note sheet material will be next described.

In the illustrative embodiment of the invention, note sheet material 3 is fed intermittently at a uniform speed, one feed step for each complete revolution of the shaft 26. In this specific embodiment, therefore, the note sheet feed may be regarded as a constant, and the feed of the pattern sheet 2 as a variable which is regulated by the apparatus next described so as to insure the proper relative positioning of the note sheet 130

material and pattern sheet for the succession of punching operations.

At the right hand margin of the pattern sheet 2 are shown three rows of perforations 5 so spaced that the distance between any one perforation and the next following perforation in another row equals the desired length of one feed step of the pattern sheet corresponding to one feed step of the note sheet 10 material. That is to say, the movement of the pattern sheet takes place in a succession of steps, each step consisting of the distance (measured parallel to the length of the sheet) between one of the marginal perforations and the next. These perforations 15 correspond to tracker vents 70, 71 and 72. As shown in the drawing, the marginal perforation 73 is about to open the tracker vent 70. Thereafter, when the pattern sheet 2 20 has moved through one of its feed steps, the perforation 74 will open the vent 71; and after another feed step the perforation 75 will open the vent 72. Then other perforations 76, 77 and 78 will repeat the operation 25 of opening tracker vents 70, 71 and 72 in succession, and these successive alternative openings of the tracker vents 70, 71 and 72 are repeated throughout the desired length of the pattern sheet. The vents 70, 71 and 30 72 are connected respectively by ducts 80, 81 and 82 with valve mechanisms V, V¹ and V². The valve mechanism V² is shown in section to disclose its interior construction; and valve mechanisms V and V¹ may be exact 35 duplicates of the mechanism V².

The duct 82 opens into a diaphragm chamber 85, the diaphragm of which operates a valve 86. The chamber 87 of the valve 86 is entered by duct 88, and a second duct 89 (shown in dotted lines). When the valve 86 40 rests in the position shown (*i. e.*, when the diaphragm chamber 85 is exhausted through the usual bleed while the tracker vent 72 is closed) there is through communication between the ducts 88 and 89, with an effect 45 presently described. When, however, the vent 72 is open, atmosphere is thereby admitted to the diaphragm chamber 85, and thereby the valve 86 is lifted to close the 50 mouth of the duct 88 and open communication between the duct 89, past the valve 86, to suction in the main exhaust chamber 90. The duct 88 is arranged to receive either atmosphere, or suction from the chamber 90, 55 according to the position of the valve 92 operated by a diaphragm of the chamber 93, which chamber is connected by a duct 95 with a controlling device, presently described, connected with the feed mechanism 60 for the note sheet material 3.

The duct 89 (shown in dotted lines) connects the valve chamber 87 with a diaphragm chamber 100, the diaphragm of which operates a valve 102. The chamber 65 103 of the valve 102 is closed to atmosphere,

and communicates with a duct 105. When the valve 102 is in the position shown, the chamber 103, and therefore the duct 105, are shut off from both atmosphere and suction, and therefore the chamber and duct contain 70 dead air. A spring 107 may be provided to assist in returning the valve 102 to the position shown after it has been moved and then released.

The duct 105 connects the chamber 103 75 with the duct 13 already referred to, which communicates with the pneumatic motor M. And it is through this duct 105 and corresponding ducts of the valve mechanism V and V¹ that the exhaust is communicated to 80 the motor to operate it. Hence when the duct 105 is cut off from the exhaust, the motor is stopped, unless exhaust is admitted to the duct 13 from one of the other valve mechanisms V and V¹.

Returning now to the duct 95—it connects the diaphragm chamber 93 with a valve block 110 which contains a cylindrical rotating valve 111 having an axial-bore 112, which is continuously open to atmosphere. 90 A radial port 113 communicates with the axial-bore 112. The duct 95 has a mouth 115 which is opened to atmosphere from time to time, in the rotation of the valve 111, by way of the port 113 and axial-bore 112. 95

The valve 111 is affixed to a gear 117, which gear is driven by a pinion 118 mounted upon the punch selecting and driving shaft 26. For the purposes of the specific illustrative apparatus, the gears 117 and 118 have 100 the ratio of three to one. That is to say, for each revolution of the shaft 26, the gear 117 and valve 111 are rotated through only one-third of a complete revolution, or 120°.

In the operation of the apparatus thus far 105 described, the shaft 26 is continuously rotated, whereby the note sheet material 3 is fed in a continuous succession of steps, and for each such step the valve 111 is rotated through 120°.

When the radial port 113 registers with the mouth 115 of the duct 95, atmosphere is thereby admitted through the duct 95 to the diaphragm chamber 93. This moves the valve 92 and admits atmosphere to the duct 88, and through the valve chamber 87 to the duct 89 and diaphragm chamber 100. This in turn lifts the valve 102 and opens the motor duct 105 and the duct 13 to suction in the main exhaust chamber 90. The applying 115 of the exhaust to the motor promptly starts the feed of pattern sheet 2. This feed movement of the pattern sheet continues until stopped as hereinafter described, by the opening of an appropriate tracker vent by 120 one of the marginal perforations in the pattern sheet.

As already stated, the valve mechanisms V and V¹ may each be exactly like the valve mechanism V², which has just been de- 130

scribed. All three of the valve mechanisms are connected respectively with the motor duct 13 by the three ducts 105, 120 and 121 respectively; and the operation of any one 5 alone of the valve mechanisms V, V¹ or V² will admit suction to the motor duct 13, and thereby start the drive of the motor and the feed of the pattern sheet 2. The valve mechanism V is connected to the tracker vent 10 70 by the duct 80 in the same manner described in connection with the valve mechanism V²; and likewise the valve mechanism V¹ is connected with the tracker vent 71 by the duct 81.

15 The duct 130, exactly corresponding to the duct 95, connects the valve mechanism V with a port 132 in the valve block 110. The duct 134, corresponding to the ducts 95 and 130, connects the valve mechanism 20 V¹ with a port 135 in the valve block 110. The ports 115, 132 and 135 are disposed 120° apart around the valve 111; and hence for each one-third of a revolution of the valve 25 111—i. e., for each complete revolution of the shaft 26—one of the ports 115, 132 and 135 is open to atmosphere. In other words, since each complete revolution of the shaft 30 26 causes one feed step of the note sheet material 3, it follows that each such feed step is accompanied by the opening of one of the three ports 115, 132 and 135.

It will be noted in the specific apparatus that suction will be admitted to the motor M to drive the same only so long as the 35 valve 102 or a corresponding valve in the mechanism V or V¹ is held up against its spring 107; and this condition would prevail only so long as the valve 92 is lifted to permit atmosphere to enter the ducts 88 40 and 89 and the diaphragm chamber 100. But to lift the valve 92 to this end, the duct 95 must receive atmosphere through its mouth 115 from the port 113 in the valve 111. In other words, the feed of the note 45 sheet by the motor M results from the opening of one of the ports 115, 132 or 135 in the rotation of the valve 111; and the supply of suction to the motor M is continued only so long as one of said ports is maintained 50 open by the rotating port 113. Thus the effect of the rotation of the valve 111, in the absence of the perforations 73, 74, 75, etc., and the valve 86, would be simply to repeatedly start and stop the motor M so as 55 to feed the pattern sheet 2 intermittently in a succession of steps.

For the purposes of this specific mechanism, the motor M and its train of mechanism for feeding the pattern sheet, are arranged to operate at high speed so that when 60 actually moving the pattern sheet travels at such a speed that its feed steps consume each considerably less time than a feed step of the note sheet material.

65 Thus at the beginning of operation of the

apparatus as a whole, the note sheet material being assembled and engaged by its feeding mechanism, and the pattern sheet being secured to the take-up roll 9, the punching machine is started; and thereby the rotation of the valve 111 is commenced. As a result, the stencil sheet is moved through a series of high speed steps until the marginal perforations 73, 74, 75, etc., reach a proper relationship to the operation of the 70 valve 111 to cause the desired arrest of the stencil sheet feed at the end of each feed step. For example, with the parts in the 75 positions shown in the drawing, the valve port 113 admits atmosphere through the duct port 135 and duct 134 to the valve mechanism V¹, and thereby admits suction through the ducts 120 and 13 to the motor. Thus as shown the motor is operating to 80 drive the stencil sheet. When the duct 70 85 is now opened by the perforation 73, the opening of that perforation admits atmosphere through the duct 80 to the valve mechanism V¹, causing a valve like the valve 86 to lift, but without any tendency to stop the 90 motor, which receives its supply of suction, not from the valve mechanism V controlled by the perforation 73 in the stencil sheet, but by the valve mechanism V¹, which is 95 not affected by the perforation 73. Therefore the stencil sheet continues its rapid 100 succession of high speed steps until it overtakes, so to speak, the valve 111, and until the opening of one of the tracker vents 70, 71 and 72 follows directly after the opening of the corresponding duct port 115, 132 or 135. For example, although in the 105 positions shown in the drawings, the perforation 73 would probably be ineffective to stop the stencil sheet feed, nevertheless by 110 the time the valve port 113 has reached and opened the duct port 115 (for the valve mechanism V²), the more rapidly moving stencil sheet would have brought the corresponding perforation 74 near to the 115 tracker in readiness to open the vent 72 (also corresponding to the valve mechanism V²). Thus the admission of atmosphere to the duct port 115 would start the drive of the motor M and its feed of the note sheet, 120 which would be moved rapidly through a feed step and until the perforation 75 had opened the tracker vent 72, whereupon the described mechanism would promptly stop the stencil sheet feed. Thereafter the succession of openings of the duct ports 115, 132 and 135 would be followed respectively and in step by the opening of the tracker vents 70, 71 and 72 by the succession of 125 perforations 76, 77 and 78. In other words, the opening of the duct port 132 will start a feed step of the stencil sheet, which will be stopped by the opening of the tracker vent 70 by the perforation 76; the opening of the duct port 135 will start a feed step 130

of the stencil sheet, which will be stopped by the opening of the tracker vent 71 by a perforation 77; the opening of the duct port 115 will start another feed step of the 5 stencil sheet, which will be stopped by the opening of the tracker vent 72 by the perforation 78; and so on throughout the series of marginal perforations in the stencil sheet.

10 As already described, each one-third revolution of the valve 111 corresponds to one feed step of the note sheet material 3. Therefore for each feed step of the note sheet material there will be a definite predetermined length of feed step of the stencil sheet; *i.e.*, a length of feed step equal to the distance (measured parallel with the length of the stencil sheet) between one perforation, 73, and the next.

15 20 To permit the stencil sheet feed to overtake, so to speak, the rotating valve 111 before the actual punching of the note sheet material begins, it is preferred that a series of perforations, 73, 74 and 75, etc., extend to some distance along the stencil sheet in advance of the initial note perforations. Thus when the note perforations reach the tracker bar 15, and start their selection of punches for perforating note sheet material, the 25 proper relationship between the stencil feed and the note sheet feed will have been established, and will thereafter be maintained. From the foregoing description it will be readily understood by those skilled in the 30 art that the stencil sheet and the note sheet material will be fed step by step, and always in step with each other; and the note sheet material (in the specific illustrative machine) will be fed through steps of uniform 35 length, while the steps of the stencil sheet will depend for their lengths upon whatever spaces are predetermined between each marginal perforation and the next. If it is desired to reproduce upon the note sheet 40 material exactly the relationship of the perforations in the stencil sheet, then the spaces between the successive marginal perforations of the stencil sheet would be made of uniform length so that the feed steps of the 45 stencil sheet would be uniform. But by varying the spaces between the marginal perforations in the stencil sheet, the note sheet may be provided with perforations having predeterminedly different relations 50 from the relations of the perforations of the stencil sheet.

It is to be understood that this invention is not limited to the specific construction, organization, or mode of operation described 55 herein for illustration. On the contrary, the invention may be variously embodied or the described construction may be variously modified within the scope of the subjoined plans. It is not indispensable that all the 60 features of the invention be used conjointly,

since they may be used to advantage separately.

Claims:

1. A note sheet perforating machine comprising, in combination, punch selecting and driving mechanism including a pattern sheet; feeding means for the note sheet material; independent feeding means for the pattern disconnected from the note-sheet feeding means; and means connected to one 75 of said feeding means for starting and stopping the other said feeding means.

2. A note sheet perforating machine comprising, in combination, punch selecting and driving mechanism including a pattern 80 sheet; feeding mechanism for the note sheet material; means for feeding the pattern; and pneumatically-operated starting means for the pattern feeding means controlled by the note sheet feeding mechanism. 85

3. A note sheet perforating machine comprising, in combination, punch selecting and driving mechanism including a pattern; separate independently driven feeding means for the pattern and the note sheet material; 90 and controlling means for one said feeding means, controlled by the other said feeding means.

4. A note sheet perforating machine comprising, in combination, punch selecting and 95 driving mechanism including a moving pattern; note sheet feeding mechanism; pneumatic means governed by the note sheet feeding mechanism for starting the movement of the pattern; and pneumatic means 100 controlled by the pattern for stopping the movement thereof.

5. A note sheet perforating machine comprising, in combination, punch selecting and driving mechanism including a pattern; 105 note sheet feeding mechanism; pneumatic means controlled by the note sheet feeding mechanism for starting a succession of feed steps of the pattern; and means for predeterminedly the length of each said step. 110

6. A note sheet perforating machine comprising, in combination, punch selecting and driving mechanism including a moving pattern; note sheet feeding mechanism; independently driven feeding means for the pattern; means governed by the note sheet feeding means for starting the pattern feeding means; and means governed by the pattern for stopping the pattern feeding means. 115

7. A note sheet perforating machine comprising, in combination, punch selecting and driving means including a pattern; pattern feeding means; note sheet feeding means; and pneumatic means for causing the respective feeding means to operate in step with each other. 120

8. A note sheet perforating machine comprising, in combination, punch selecting and driving mechanism including a pattern; a motor for feeding the pattern; independ- 125

- ently driven note sheet feeding mechanism; and controlling mechanism for said motor governed by said note sheet feeding mechanism.
5. 9. A note sheet perforating machine comprising, in combination, punch selecting and driving mechanism including a pattern; note sheet feeding mechanism; independently driven pattern feeding mechanism; 10 means for starting pattern feed steps corresponding to note sheet feed steps; and means controlled by the pattern for determining the lengths of pattern feed steps.
10. A note sheet perforating machine comprising, in combination, punch selecting and driving mechanism including a pattern; pneumatic pattern feeding mechanism; independently driven note sheet feeding mechanism; means for starting a succession of 15 pattern feed steps corresponding to note sheet feed steps; and means carried by the pattern for determining the lengths of pattern feed steps.
11. A note sheet perforating machine comprising, in combination, punch selecting and driving mechanism including a pattern; note sheet feeding mechanism; a motor disconnected from said note sheet feeding mechanism for feeding the pattern; and 20 starting and stopping mechanism for said motor synchronized with the note sheet feeding mechanism.
12. A note sheet perforating machine comprising, in combination, punch selecting and driving mechanism including a pattern; note sheet feeding mechanism; a pneumatic motor for feeding the pattern; a starting and stopping mechanism for said pneumatic 25 motor connected to the note sheet feeding mechanism.
13. A note sheet perforating machine comprising, in combination, punch selecting and driving mechanism including a pattern; note sheet feeding mechanism; a pneumatic 30 motor for feeding the pattern; means for starting the pneumatic motor; and means controlled by the pattern for stopping said motor.
14. A note sheet perforating machine comprising, in combination, punch selecting and driving mechanism including a pattern; note sheet feeding mechanism; a pneumatic 35 motor for feeding the pattern; means connected to the note sheet feeding mechanism for starting the pneumatic motor; and perforations in the pattern for stopping said motor.
15. A note sheet perforating machine com-
- prising, in combination, punch selecting and driving mechanism including a pattern; note sheet feeding mechanism; a motor disconnected from said note sheet feeding mechanism, for feeding the pattern; means for starting said motor a succession of times corresponding to successive feed steps of the note sheet material; and a succession of devices on the pattern for successively stopping said motor; successive spaces between said devices determining lengths of feed steps of the pattern.
16. A note sheet perforating machine comprising, in combination, perforating mechanism; a pattern having operative connection with the perforating mechanism; driving means for the perforating mechanism; independently driven means for feeding the pattern; and means connected with the perforating mechanism for governing the pattern feed.
17. A note sheet perforating machine comprising, in combination, perforating mechanism; selecting mechanism; separate driving means for said mechanisms respectively; and means for maintaining said mechanisms in desired correlation and having operative connection with and controlled by both said mechanisms.
18. A note sheet perforating machine comprising, in combination, perforating mechanism; selecting mechanism including a pattern; separate driving means for the perforating mechanism and pattern respectively, and means for maintaining the perforating and selecting mechanisms in desired correlation; including means operatively connected to and controlled by the drive for the perforating mechanism for starting the pattern drive, and means operatively connected to and controlled by the pattern for stopping the pattern drive.
19. A note sheet perforating machine comprising, in combination, perforating mechanism, selecting mechanism including a pattern; mechanism for driving said perforating mechanism and pattern; means for starting the pattern drive in predetermined time relation to the perforating mechanism; and means to stop the pattern drive with the pattern in a predetermined position.
- In testimony whereof, I have signed my name to this specification, in the presence of two subscribing witnesses.
